LATCH STRUCTURE

Edward D. Dall, Detroit, Mich., assignor to Hou-daille-Hershey Corporation, Detroit, Mich., a corporation of Michigan

Application May 23, 1940, Serial No. 336,696

6 Claims. (Cl. 292—99)

This invention relates to latch structure adapted particularly for latching in closed position the covers or hoods of the engine enclosing housing on automotive vehicles such as automobiles.

An important object of the invention is to provide improved structure and arrangement in which a latch lever is mounted on the housing body in the path of a keeper on the hood or cover with the operation such that when the cover is moved to its closing position the keeper will engage with the latch lever to move it to its latching position, together with means operable only from within the vehicle body for effecting unlatching of the latch lever.

A further object is to provide cross-center spring means for quickly completing the latching or unlatching movement of the latch lever and with the spring means effective, after unlatching movement of the latching lever, to hold the latching lever against the keeper with the hood or cover open sufficiently for insertion thereunder of the fingers or hand so that the unlatched cover may be readily swung to its fully opened position.

Another important object is to cause the spring means to continue its pressure against the latching lever after latching movement thereof into engagement with the keeper so as to force the cover against its seat and to take up any slack, so that the hood or cover will be securely held closed against rattling.

A further object is to provide detent means for positively locking the latching lever against unlatching movement thereof and with the detent operable only from inside of the vehicle for release of the latching lever for movement thereof to unlatching position.

Another important object is to provide simplified structure that can be economically manufactured and installed and which will operate efficiently at all times.

The various features of the invention are incorporated in the structure shown on the drawings, in which drawings:

Figure 1 is an inside elevation of the lock structure mounted on the inside of a side wall of the housing, and the keeper on the cover;

Figure 2 is a section on plane II—II Figure 1;

Figure 3 is an inside elevation of the latching structure on the housing showing the unlatching position; and

Figure 4 is an end view.

The latch structure on the housing wall comprises a supporting base or plate 10 having flanges 11 at its upper edge by which it is secured, as by

bolts or rivets 12, to the sill 13 extending inwardly from the side wall 14 of the housing, the plate 10 being thus suspended from the sill.

The plate 10 has the extension 15 at its top to which is secured a stud 16 for fulcruming the latching lever 17. The lever has the outer hooked end 18 for latching engagement with a keeper 19 shown on the drawings as a cylindrical stud or pin extending from a base 20 secured against the top of the seating flange 21 along the lower edge of a hood or cover 22, the seating flange 21 engaging against the sill 13 of the housing wall 14 when the hood is in closed position as shown in Figure 1.

Figure 1 shows the hook end of the latching lever in latching position in engagement with the keeper 19 to hold the hood 22 closed. Opposite the hook end 18, the latching lever has the arm 23 presenting the shoulder or edge 24 which, when the latching lever is moved toward unlatching position, engages the keeper stud 19 to raise the cover 22 a distance away from the sill 13 so that the fingers or the hand may be inserted below the cover for swing thereof to full open position, as shown on Figures 3 and 4.

At its inner end, the latching lever has the hole 25 receiving the head of a pin or stud 26 whose reduced end 27 extends through the slot 28 in the plate 10 and receives a bushing 29 engaging in the slot, the slot being arcuate with its center at the axis of the fulcrum 16. When the latching lever is rotated to its latching or unlatching position, the bushing 29 will travel along the slot 28 to limit the swing of the latching lever. A link 30 extending downwardly behind the plate 10 is journaled at its upper end on the bushing 29 and is held in place against the back of the plate 10 by the bushing flange 29', the inner end of the pin end 27 being riveted over against the bushing.

A coiled spring 31 is anchored at its inner end to the plate 10 at the rear side thereof, the outer end of the spring abutting the lower end of the link 30 and at all times exerting upward thrust on the link, the link having a stud 32 extending therefrom into the guide slot 33 in the plate 10. When the latching lever 17 is swung to its latching or unlatching position, the bushing 29 travels through the slot 28 past the line extending between the lever fulcrum 16 and the spring abutment end of the link, and as soon as the bushing travels to either side of this line, the thrust of the spring will become effective to quickly snap the latching lever into its latching position shown on Figure 1, or to its unlatching position shown on Figure 3.

Journalled at its upper end on the pin body 26

is a pawl 34 having the corner or tooth 35 at its lower end for engaging with rack teeth 36 on a bar 37 secured to the plate 10, the rack teeth being in an arcuate row concentric with the fulcrum 16 of the lever 17. The tail end of the lever 17 is deflected to form an abutment 38 for the wing 39 on the pawl 34, and a hairpin spring 40 anchored on a stud 41 on the lever 17 engages the pawl and the lever and tends to swing the pawl with its wing 39 against the abutment 38 when the lever is in its unlatching position. The pawl is held against the lever by the head 26' of the pin body 26.

The lever 17 has the arm portion 42 deflected therefrom to be in the plane of the pawl 34 and to form an abutment for engagement by the pawl when the pawl is swung away from the rack teeth 36. At its lower end, the pawl has the post 43 to which is secured the end of a pull member, such as a wire 44. In accordance with my invention, this wire extends to a button 45 which may be at the instrument panel 46, with the arrangement such that when the button is pulled out the pawl 34 will be swung for release from the rack teeth 36 and for engagement with the arm 42 of the latching lever for swing of the latching lever to its unlatching position. As soon as the pin 26 passes through the neutral stress line of the spring 31, the latching lever will be quickly snapped to its unlatching position. As the lever is swung toward its unlatching position, the hook end 18 of the lever is withdrawn from the keeper stud 19 and the lever shoulder 24 engages the stud so that, when the latching lever has reached its unlatching position, the hood 22 will have been raised a distance away from the sill 18, as shown on Figure 4, so that the fingers may be inserted below the hood edge for swing of the hood to its fully opened position.

When it is desired to close the hood, it is swung down to closed position, the keeper stud 19 then engaging the shoulder 24 to swing the lever toward its latching position, and when the neutral stress line of the spring 31 is passed, the spring pressure against the link 30 will cause the latching lever to be quickly snapped into its latching position, as shown on Figure 1. During movement of the lever to latching position, the pawl tooth 35 will travel along the rack teeth 36 and when the lever is in latching position the pawl tooth 35 will be above one of the rack teeth 36 and the latching lever will be locked against unlatching movement, and can be released for unlatching movement only by operation of the button 45 within the vehicle body and thereby release of the pawl from the rack teeth. The pawl thus forms a detent for positively locking the latching lever in its latching position.

The movement of the latching lever to unlatching position is limited by the engagement of the bushing 29 with the lower end of the slot 28. The upper end 28' of the slot 28 is not engaged by the bushing 29 when the lever is in latching position, nor is the stud 32 on the link 30 in engagement with the upper end of the guide slot 28 when the latching lever is in its latching position. This clearance in the slots 28 and 33 is provided so that the thrust of the spring 31 is communicated through the link 30 entirely to the latching lever so that the hook end of the latching lever will continue to exert downward pressure against the keeper stud to take up any slack between the hood and the housing and to hold the hood securely closed and against rattling. If packing material is provided

on the hood or the housing sill, the spring pressure against the latching lever will hold the packing compressed so as to form a sealed joint between the hood and housing. It will be noted on Figure 1 that when the latching lever is being forced by the spring thrust to hold the hood securely closed, the lower end of the detent pawl 34 may move upwardly a distance from the corresponding rack tooth 36. However, the spring 30 will hold the pawl in position above the tooth so that the latching lever cannot be swung to unlatching position until the button 45 is operated from within the automobile body to release the detent pawl from the rack teeth.

If the spring 31 should become broken, or disconnected from the link 30, the latching bolt can be swung to its unlatching position entirely manually by pull on the button 45, and when the open hood is swung down to closed position, the latching lever will be swung to its latching position and locked in such position by the detent pawl 34. Should the spring 40 become broken or displaced, the detent pawl will operate by gravity to effect locking of the latching lever in latching position.

Only one or a number of latches may be provided at each side of the hood supporting housing, and on each side a separate wire may extend from each detent pawl to the corresponding button or a common wire may be connected with the detent pawls so that the pawls on each side may be simultaneously operated by pull on the button for release of the latching lever.

I have shown a practical and efficient embodiment of the features of my invention, but I do not desire to be limited to the exact construction, arrangement and operation shown and described as changes and modifications may be made without departing from the scope of the invention.

I claim as follows:

1. Latching structure for a swinging cover of a housing on an automotive vehicle comprising keeper means on the cover, a latching lever on the housing rotatable for latching engagement with the keeper means or for unlatching thereof, a swinging detent pawl depending from said lever, a detent abutment on said housing engageable by said detent pawl when said lever is rotated into latching position whereby said lever will be locked against rotation in unlatching direction, an abutment on said lever, and means operable from a point remote from said lever for first effecting release of said detent pawl from said detent abutment and for then engaging said detent pawl with said lever abutment for rotation of said lever to unlatching position, and means on said latching lever effective during unlatching movement of said lever to engage with said cover to raise it to a partially open position.

2. Latch structure for latching the cover of a housing on an automobile vehicle comprising keeper means on the cover, a rotatable latching lever fulcrumed on the housing and having a latching end for latch engagement with said keeper means to hold the cover closed, a shoulder on said lever engageable with said keeper means to raise said cover to partially open position when said lever is rotated to unlatching position and to be engaged by said keeper means to rotate said lever into latching engagement when the cover is moved to closed position, a detent pawl mounted on said lever to swing thereon, an abutment bar, a spring tending to swing said detent pawl into engagement with said abutment bar when said lever is rotated to latching po-

sition and to thereby lock said lever against rotation in unlatching direction, an abutment on said lever, and releasing means operable to first swing said detent pawl away from said detent abutment and then against said lever abutment for rotation of said lever to unlatching position.

3. Latch structure for the cover of a housing on an automotive vehicle comprising keeper means on the cover, a rotatable latching lever fulcrumed on the housing and having a latching end for engagement with the latching means to latch the cover closed, a shoulder on said lever engageable with said cover to partially open said cover when said lever is rotated to unlatching position and to be engaged by said keeper means to effect rotation of said lever toward latching position when said cover is swung to closed position, spring operated means effecting the final movement of said lever to latching or unlatching position, a detent mounted on said lever for 10 swinging movement, a detent abutment engageable by said detent when said lever is rotated to its latching position whereby to lock said lever against rotation in unlatching direction, an abutment on said lever, and means actuatable from a 15 point remote from said latch structure for effecting swing of said detent away from the detent abutment to unlock the latching lever and then against said lever abutment for rotation of the lever toward unlatching position and for final 20 movement of said lever to unlatching position by said spring operated means.

4. Latch structure for latching the cover of a housing on an automobile vehicle comprising keeper means on the cover, a supporting base on the housing, a latch lever fulcrumed intermediate its ends on said supporting base, said lever at its outer end having a latching arm for engagement with the keeper means to hold the cover closed when the latch bolt is moved to its latching position, said latching lever at its outer end having a shoulder engageable with said keeper means for effecting partial opening of the cover when said latching lever is moved to unlatching position, a 25 detent member extending from the inner end of said latching lever, a latching abutment on said supporting base cooperable with said detent member to lock the latching lever in its latching position, releasing means operable to first swing said detent member away from said detent abutment to unlock said latching lever and then to engage with said latching lever to effect movement thereof to unlatching position and the engagement of said latching lever shoulder with the keeper structure for partial opening of the cover, 30 and crossover spring means applied to the inner end of said latching lever for effecting quick movement thereof into its latching or unlatching position and to exert spring pressure against said latching lever after latching thereof to hold the 35 cover closed and against rattling.

5. Latch structure for latching the cover of a housing on an automobile vehicle comprising keeper means on the cover, a supporting base on the housing, a latch lever fulcrumed intermediate its ends on said supporting base, said lever at its outer end having a latching arm for latching engagement with said keeper means to hold 40

the cover closed and having a shoulder engageable with the keeper means to effect partial opening of the cover when the latching lever is moved to unlatch the cover, a detent member pivoted to and extending from the inner end of said latching lever and a detent abutment on said supporting base cooperable with said detent member to lock the latching lever in its latching position, releasing means operable to first swing said detent member away from said detent member for unlocking of said latching lever and for then engaging with said latching lever to move it toward its unlatching position for unlatching of the cover and partial opening thereof by said shoulder, a link pivoted to and extending from the inner end of said latching lever and at its free end having slidable pivotal connection with said supporting base, and a spring engaging the free end of said link for exerting pressure through said link against the inner end of said latching lever for effecting quick movement of said latching lever to its latching or unlatching position after initial movement of said lever to such position.

6. Latch structure for latching the cover of a housing on an automobile vehicle comprising keeper means on the cover, a supporting base on the housing, a latching lever fulcrumed intermediate its ends on said supporting base and having a latching arm at its outer end for co-operation with the keeper means to hold the cover closed and having a shoulder at its outer end engageable with the keeper means to effect partial opening of the cover when the latching lever is moved to unlatch the cover, a stud carried by the inner end of said latching lever and said supporting base having an arcuate slot through which said stud extends and for limiting the movement of said lever in latching or unlatching direction, 45 a link pivoted to and extending from said stud and having sliding pivot connection at its free end with said supporting base, said stud being movable in said slot to either side of a line extending between said lever fulcrum and said link pivot connection with said supporting base, a spring exerting pressure through said link against said stud whereby after passage of said stud past said line said latching lever will be quickly moved into its latching or unlatching position, releasing means operable from a point remote from said latch structure for moving said latching lever for movement of said stud past said line whereby the spring pressure will then quickly move said latching lever to its unlatching position for functioning of said shoulder for partial opening of said cover, said shoulder upon closure movement of said cover being engaged by the keeper means to cause movement of said latching lever toward latching position and for final movement of the lever to latching position by said spring pressure, said stud after relatching of the cover being short of the corresponding end of the slot whereby said spring pressure will continue so as to cause said latching lever to take up any loose motion of the cover and hold it securely latched in closed position against rattling.

EDWARD D. DALL.
